[57] CLAIM

The ornamental design for a fishing line loader, as shown and described.

DESCRIPTION

FIG. 1 is a perspective view of a fishing line loader, showing our new design;

FIG. 2 is a back elevational view thereof;

FIG. 3 is a front elevational view thereof;

FIG. 4 is a bottom plan view thereof;

FIG. 5 is a top plan view thereof;

FIG. 6 is a left side elevational view thereof, a right side elevational view being a mirror image of the left side elevational view;

FIG. 7 is a perspective view of a second embodiment;

FIG. 8 is a back elevational view thereof;

FIG. 9 is a front elevational view thereof;

FIG. 10 is a bottom plan view thereof;

FIG. 11 is a top plan view thereof; and,

FIG. 12 is a left side elevational view thereof, a right side elevational view being a mirror image of the left side elevational view.
